UNITED STATES PATENT OFFICE.

THOMAS P. MURPHY, OF NEW YORK, N. Y.

BANK-LOCK.

Specification of Letters Patent No. 9,757, dated May 31, 1853.

To all whom it may concern:

Be it known that I, THOMAS P. MURPHY, of the city and county of New York and State of New York, have invented a new 5 and useful Improvement in the construction of Bank-Locks; and I do hereby declare that the following is a full, clear, and exact description of the construction and operation of the same, reference being had to the 10 annexed drawings, making a part of this specification, in which—

Figure 1, Plate 1, is a plan view of the lock shown with the back down and the cap off. Fig. 2, Plate 2, is a plan view of the 15 bolt with the several parts attached; Fig. 3, Plate 2, is an elevation of the cases containing the racks and sectors, Fig. 4, Plate 2, is an elevation of the racks and sectors with parts of the bolt and pressure plate and 20 pressure bolt in their places, Fig. 5, Plate 2, is a plan view of the racks and sectors with the pressure plate and pressure bolt in their places, Fig. 6, Plate 2, is an elevation of a 25 sector and pressure plate with the spring showing the action of the spring on the sectors.

The following is a description of the different parts, like letters referring to like parts.

20 A A A A, Fig. 1, Plate 1, is the rim of the lock case.

B B B B is the lock bolt extending through the case of the lock.

C is a column or stand that supports the 35 arbor that communicates motion to the bolt.

D is the outer end of the arbor with a squared hole in it to admit of the wrench E to turn it.

F is the cap of the case containing the 40 racks having a top which is intended to stand flush with the surface of the door when the lock is placed. This top having in it a mortise G allowing the racks to extend to the surface so as to admit of the key 45 being applied directly to them.

H is the key formed of any convenient number of bits for the purpose of changing the form of it and varying the arrangement of the lock.

50 I I I I I are the racks which extend flush with the surface of the key hole in front and back nearly to the bottom of the rack case they being supported by springs and levers, the racks have on their edges next 55 to the sectors geared teeth of the same pitch as the grading of the key.

K K K K K are the sectors that are supported in the case L by an arbor passing through their centers and allowing them to turn freely. The sectors have teeth on nearly one half of their periphery to match the teeth in the rack. They also have an opening on the opposite side to the teeth to permit the pressure plate to enter them.

M is the pressure plate supported by its 60 bearings in the stands at O O. To the pressure plate is attached the pressure bolt N, a rod extending to P, as a stop screwed on to the bolt B. The office of this rod is to rise and prevent the lock bolt being pushed 65 back when there is an attempt to pick the lock and the bolt is forced backward.

R R is a stand fastened to the bolt having in it a groove to allow the slide to pass 70 freely in it.

S is the slide working in the stand having in it a small pin T to enter into holes in another slide that is supported on the rack case.

U is the slide on the rack case having 80 in it a screw passing to the side of one of the racks and partaking of its motion when the key is applied. It also has in its outer side holes to admit the pin T.

W is a flat spring fastened to the pressure 85 plate either top or bottom in order to open when there is pressure applied and the sectors moved.

X is a bed piece upon which the rack case is fastened and on which the case containing 90 the sectors slide when the bolt is moved.

In explaining the operation of the lock I will take it in the position of unlocked or when the bolt is back. The key H is applied by pushing it into the key hole against 95 the racks the bits of the key each touching the end of a rack and pressing it in to correspond with its length. The sectors when the bolt is back or unlocked are in the position shown in Fig. 3, having the pressure plate M in each of the slots of the sector. It will be seen that the pressure plate is formed so as to extend nearly the distance that the sectors move in the act of locking, 100 to that just as the teeth of the racks catch the teeth of the sectors the other side of the sectors pass off of the plate which leaves them free to turn. The lock bolt B is hung on the pivot b at c which fastens it by a flexible joint to the sectors case, giving to 105 the sectors the same motion as the lock bolt.

Now by pushing in the key and applying

the wrench motion will be given to the bolt forward which carries the sector case forward so as to allow the teeth in the sectors to mesh into the teeth in the racks and when 5 the key is withdrawn the sectors are arranged in various positions by the racks coming out in their first position. At the same time that the key is applied the slide U is depressed and when the bolt is pushed 10 forward the pin T in S enters one of the holes in V, thereby fastening U and S together so that in the act of unlocking the same bitt must be applied in order that the slide S will pass the projection on the rack 15 case. In this position the bolt is locked.

It will at once be seen that the same key must be used in unlocking that was used to lock it, for the sectors must have their openings so as to admit the plate as well as the 20 slide to pass the projection on the rack case.

It is a common method in picking locks to get a pressure on the bolt and then by means of a probe or any other suitable instrument arrange the interior of the lock so 25 as to push back the bolt. In this lock it will be perceived that I have arranged the several parts so that if a pressure is applied

to the bolt before the right key is pushed in that the pressure bolt will rise and touch the stop so as to prevent the bolt from being 30 unlocked. At the same time the spring will be affected by the motion of the sectors and open from the pressure plate and prevent its going into the sectors, the operation of which may be seen by pressing against the 35 end of the bolt or turning the wrench at the same time pushing down the racks with any convenient instrument. The operation of unlocking will at once be seen by thrusting in the key and turning the wrench the 40 reverse of locking.

The following is what I claim and wish to secure by Letters Patent:

1. I claim the slides S and U and pins T operated in the manner described. 45
2. I claim the pressure plate, pressure bolt and spring attached to the plate arranged and operating as described or in any other way substantially the same and for the purpose set forth.

THOMAS P. MURPHY
